UNITED STATES PATENT OFFICE.

DANIEL CRANE, OF SAGINAW, MICHIGAN, ASSIGNOR TO HIMSELF AND
CHARLES A. LEE, OF SAME PLACE.

IMPROVEMENT IN FRUIT-CRATES.

Specification forming part of Letters Patent No. 142,148, dated August 26, 1873; application filed
June 28, 1873.

To all whom it may concern:

Be it known that I, DANIEL CRANE, of Saginaw, in the county of Saginaw and State of Michigan, have invented a new and useful Improvement in Crate for Fruit, Vegetables, &c., of which the following is a specification:

The object of this invention is to provide means for holding and protecting fruits, vegetables, and similar commodities in the course of transportation, storage, or sale; and it consists of a crate constructed of slats and heads secured together, as hereinafter described.

In the drawing, Figure 1 represents an outside view of a crate constructed according to my invention. Fig. 2 is an outside view of a portion of the crate, showing the gains which receive the heads and the wires or cords. Fig. 3 is a cross-section of Fig. 1 taken on the line *xx*.

Similar letters of reference indicate corresponding parts.

A represents the staves or slats, placed a suitable distance from each other, according to the use for which the crate is intended, and in number according to the size or diameter desired. B represents the heads, two or more in number, according to the size and number of compartments of the crate. These heads are plain disks, of either wood or metal, but preferably of wood. The heads are secured in the groove *c* of the staves. The edge of the head and the groove may be in any form, either right-angled gains and straight edges, as seen in the drawing, or V-shaped, like the croze and head of a barrel. The requisite number of staves or slats to surround the heads are connected together by means of wires or cords D. The strands of the wires or cords are twisted together between the staves, as a provision

for keeping them in proper position. The strands of which the wires or cords C are composed are thus on each side of the staves and in the gains, as seen in Fig. 1. When the staves are thus connected by the wires they are wrapped around the heads and the two outside staves are secured together by the sliding gripes E, one or more for each head.

The operation of this gripe is most plainly seen in the section, Fig. 3.

By slipping this gripe back from the head the staves may be sprung up and the head readily removed, and it is as readily replaced and secured when the gripe is replaced.

All the heads may be removed by sliding the gripes therefrom, when the staves may be rolled up together and the whole crate made to occupy but little space in return-transportation or storage when not in use.

Instead of gains or grooves in the staves, pins or nails may be employed to keep the heads in position, but I prefer the gains or grooves.

The advantages are that fruits or vegetables confined in these crates are well ventilated and well protected, and the crate may be "knocked down" and put together with perfect ease and facility.

Having thus described my invention, I claim as new and desire to secure by Letters Patent—

The combination, with a series of staves arranged in grooves of heads B, of the flexible binders C and gripers E, as and for the purpose described.

DANIEL CRANE.
